UNITED STATES PATENT OFFICE

2,550,883

BUILDING STRUCTURE

Clarence Joseph St. Vincent, Norway, Mich.

Application May 28, 1947, Serial No. 750,933

4 Claims. (Cl. 20—4)

1

This invention relates to new and useful improvements in building structures and the primary object of the present invention is to provide a log cabin structure including means for retaining the uprights forming the wall thereof in a tight manner, to prevent water from passing between adjacent uprights.

Another important object of the present invention is to provide a building structure so designed as to eliminate the usual need of screws, nails and other fastening means for retaining said uprights in a fixed position.

A further object of the invention is to provide a building structure embodying novel and improved means for insulating the walls thereof.

A still further object of the present invention is to provide a collapsible building structure that is simple and practical in construction, strong and reliable in use, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a fragmentary perspective view of a wall constructed in accordance with the present invention, and said wall also being provided with a door and window;

Figure 2 is a fragmentary group perspective view showing the manner in which the wall displayed in Figure 1 is constructed;

Figure 3 is a fragmentary side elevational view showing the lower portion of the building structure supported on a footing; and,

Figure 4 is a fragmentary top plan view showing the manner in which adjacent walls are joined.

Referring now to the drawings in detail, wherein for the purpose of illustration, there is disclosed a preferred embodiment of the present invention, the numeral 10 represents a plurality of logs, used in conjunction with the present invention, having their outer faces 12 scalloped or rounded and with the other faces of said logs being substantially flat. These logs are disposed vertically in juxtaposed position to form a wall designated generally by the numeral 14, and best shown in Figure 1 of the drawings.

The opposing vertical faces of these logs are provided with longitudinal grooves or channels 16 that receive substantially flat retaining or

2

wedge strips 18 to hold adjacent logs in a vertical plane without shifting movement.

The terminal portions of these retaining strips project upwardly from the upper ends of the logs and are fitted into a longitudinal groove 20 provided in the underside of an upper plate 22 bearing on the upper ends of the logs.

Aligned longitudinal grooves 24 are provided in the upper ends of the logs and receive a horizontally disposed retaining strip 26, with a portion of this retaining strip 26 projecting upwardly from the upper ends of the logs to frictionally fit into a second longitudinal slot 28 provided in the underside of plate 22.

15 To increase the thickness of the upper plate 22 and to add to the appearance of the structure, a second plate 30 overlies plate 22 and is secured thereto by a retaining strip 32 frictionally fitted into aligned grooves 34 provided in the opposing faces of plates 22 and 30.

In the construction of a building with the above material, a concrete footing 36 is preferably first laid in a trench outlining the building.

A base plate 38 is preferably anchored to the 25 upper face of the footing in any suitable manner with a second base plate 40 disposed above and suitably secured to the upper face of plate 38. This second base plate 40 is provided with a pair of spaced parallel longitudinal grooves 42 one of 30 which opposes a longitudinal groove 43 provided in the lower ends of the logs and retaining strips 44 are frictionally inserted in these opposing grooves to hold the logs secured to each other at their lower ends.

35 Reference is now directed to Figures 1 and 3 more particularly, wherein there is disclosed the manner in which the door openings and window openings are constructed.

The tread 46 for the doorway is provided with 40 a longitudinal groove 48 in its underside that receives the upstanding portion of retaining strip 44 and the ends of the tread abut the outer faces of the end logs forming the sides of the doorway.

The side pieces 50 for the door are provided 45 with a groove 52 in their inner faces that receive the outer portion of retaining strip 18 carried by the logs at the side of the door opening.

A longitudinal retaining strip 54 projects 50 downwardly from the lower ends of the logs outlining the upper opening of the door, and this retaining strip 54 engages the upper piece (not shown) for the door frame.

An opening 56 is cut in the side wall 14 to provide a window opening and a portion of retaining strip 58 projects outwardly from the oppos-

ing ends of the legs outlining the top and bottom of the window opening to fit into a longitudinal groove 60 in the inner faces of both the upper portion 62 and bottom portion 64 of the window frame, with the ends of the retaining strips 18 also projecting outwardly from opposing ends of the logs to fit into a second longitudinal slot 66 in the inner faces of both portions 62 and 64.

The side portion 68 for the window frame is provided with a groove (not shown) for receiving the outwardly projecting portion of strips 18 of the logs at the sides of the window opening.

Reference is now directed to Figure 4, wherein there is shown that vertical strips 10 are suitably secured to the inner faces of the logs to prevent seepage of water through the abutting faces of the logs.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described.

Having described the invention what is claimed as new is:

1. A wall structure comprising a plurality of logs, said logs being arranged vertically in juxtaposed position and having opposing vertical faces, vertical grooves provided in the opposing vertical faces of said logs, flat retaining strips fitting in opposing grooves to retain adjacent logs relative to each other, aligned longitudinal grooves in the upper ends of said logs, a horizontally disposed retaining strip fitting in said aligned grooves and preventing endwise movement of the logs, a portion of said last strip with respect to each other projecting upwardly from said logs, and a header plate having longitudinal grooves in its bottom face receiving the last mentioned retaining strip, said header plate being held against the upper ends of said logs by said horizontal retaining strip, and said vertical strips having upper ends fitted in one of said longitudinal grooves to further hold the header plate against the upper ends of said logs.

2. A wall structure comprising a plurality of vertical logs each having a pair of flat vertical side faces and a flat vertical inner face, said logs being arranged in juxtaposition with a side face of one log abutting a side face of an adjacent log, the abutting side faces of said logs having registering grooves therein, flat retaining strips joining adjacent logs and being fitted in said registering grooves, said logs each having a horizontal groove in their upper ends, said horizontal grooves being aligned with each other, a horizontally disposed retaining strip seated in said horizontal grooves and joining all of said logs together and aiding the vertical strips in retaining a flat side face of one log against a flat side face

of an adjacent log, said logs having upper flat end surfaces, a flat header plate resting upon the upper end surfaces of said logs and having a pair of horizontal channels therein, said vertical strips including upper ends projecting above the upper ends of said logs and fitting in one of said channels to hold the header plate against the upper ends of said logs, said horizontal strip including an upper edge projecting above the upper ends of said logs and fitting in the other of said channels to aid in retaining the header plate against the upper ends of said logs, and vertical batten strips secured to the inner faces of adjacent logs and extending across the abutting side faces of adjacent logs.

3. A wall structure comprising a plurality of vertically disposed logs lying in side by side relationship and including flat upper and lower horizontal ends, adjacent logs including opposed flat vertical faces engaging each other throughout their length, said opposed vertical faces having registering vertical grooves extending through the length of said logs, vertical retaining strips fitted in said registering vertical grooves and joining adjacent logs, said vertical strips including upper and lower ends projecting outwardly from the upper and lower ends of said logs, the upper and lower ends of said logs having horizontal grooves therein, said horizontal grooves in the upper ends of the logs being in longitudinal alignment with each other and the horizontal grooves in the lower ends of said logs also being in longitudinal alignment with each other, upper and lower horizontally disposed retaining strips fitted in said upper and lower horizontal grooves and including outer longitudinal edges projecting outwardly from the ends of said logs, upper and lower headers each having a pair of spaced parallel channels, said upper header resting against the upper ends of said logs and the channels in said upper header receiving the longitudinal edge of said upper retainer strip and the upper ends of said vertical strips to hold the upper header to the upper ends of the logs, the channels in the lower header receiving the lower ends of the vertical strips and the outer edge of said horizontal strip to hold the lower header against the lower ends of said logs, and vertical batten strips secured to and joining adjacent logs.

4. The combination of claim 3 wherein said logs have rough exterior surfaces and finished interior surfaces.

CLARENCE JOSEPH ST. VINCENT.
